SHAVING DEVICE

Rudolf Naegeli, Bern, Switzerland

Application May 14, 1941, Serial No. 393,444
In Switzerland May 22, 1940

14 Claims. (Cl. 30—43)

The present invention relates to a shaving device in which the operating motor is enclosed within the handle.

The invention relates particularly to such devices where a shaving blade of conventional rectangular form is moved to and fro between holding and protecting elements and with its cutting edge in direct contact with the skin. The cutting edge of the blade slides upon a stationary supporting plate provided with cutting edges formed by holes and recesses having sharp edges in the path of the blade, said holes and recesses acting as retaining means for the hair extended into said holes or recesses, so that the hair is caught and cut by the cutting edges of the blade and said holes and recesses and so that also the portions of the skin carrying said hair are held fast by said holes and recesses during the cutting of the hair.

A further object of the invention is to have a shaving device where the blade is moved at an acute angle with regard to the supporting plate so that it alternately overlaps and uncovers the holes and gives to the hair free access while the cut hair falls outside of the head.

Another object of the invention is a shaving device where the shaving blade can be axially displaced with its operating device and is pressed resiliently upon the supporting plate all with the aim to secure the tight contact between the cutting edges of the blade and the edges of the holes and recesses and to permit the removal of the blade from the plate.

Still another object of the invention is the combination of the shaving device with a hair cutting device all in the same tool and to have the hair cutting blade moved either parallel to a hair cutting comb or at an acute angle.

The present device may be used for wet or dry shaving while using soap or cream.

In the annexed drawings are represented several embodiments of the invention.

Fig. 1 is a longitudinal section of the head of the shaving device.

Fig. 2 is a side elevation.

Figs. 2a and 2b are transverse sectional views showing different forms of blades.

Fig. 3 a plan of the shaving tool partly broken away.

Fig. 4 is a longitudinal section through the head of a modified device.

Fig. 5 is a side elevation.

Figs. 5a and 5b are transverse sectional views of different forms of blades.

Fig. 6 is a plan having cover and blade removed.

Fig. 7 shows a bottom view of the head, the supporting screws for the motor being shown in section.

Fig. 8 is a longitudinal section through the head of a shaving device combined with a hair cutting device.

Fig. 9 shows a side elevation of the device shown in Fig. 8.

Figs. 9a and 9b are transverse sectional views showing varied forms of blades.

Fig. 10 is a plan of a modified form of combined shaving and hair cutting device with the cover and blade removed. Fig. 11 is a similar view of the device shown in Fig. 8.

15 Similar letters of reference indicate similar parts. According to the Figs. 1 to 7 the shaving device designated at B is removably attached to a hollow head A. The lower portion of the head A, as shown in Fig. 7, is provided with two spaced and externally threaded extensions E of segmental form which are screwed into the internal threads of the handle C and two screws E¹ support the motor D in position with respect to the extensions E. Between the electric motor D and the

20 inside walls of handle C a free space F is left permitting the circulation of the air for cooling of the stator. The air is admitted at the bottom of the handle and passes through said free space F and leaves the top of the apparatus. Head A and handle C are preferably made of Bakelite or another suitable pressed material. The shaving device B is made of a hard non-corrosive steel or may be protected against corrosion by nickel-plating or chrome-plating. The

25 shaving tools comprise a plate I fixed to the head A by means of bolts 2, lock members 3 and screws 4, said plate having a longitudinal edge 5 provided on each side with a row of holes or recesses 6 of any suitable form. The plate I (see Fig.

30 2a) is somewhat hollowed out in a longitudinal direction at the middle portion of its upper surface and the two longitudinal borders are somewhat inclined towards the center so that a flat shaving blade 7 laid upon the plate makes contact therewith only at the outer cutting edges and

35 with the edges of the holes 6. The cutting edges of the shaving blade may be sharpened on both sides or only on one side. The spacing of the rows of holes and recesses 6 is such that the cutting edges of the blade in its extreme position are moved a little distance over the outer edges of the holes to secure the complete cutting off of the hair projecting into the holes. The plate I is provided at its middle portion with a

40 longitudinal opening 8 through which the pins

45

9, 10, 11 of the motor driven slide 12 extend into the holes of the blade 7. Slide 12, having two lateral guides 13 and 14 arranged at an acute angle with regard to the middle line of head A, is disposed beneath the fixed plate 1. The pins 9, 10 and 11 are cylindrical and are fast in the slide 12 and being engaged in holes in the blade 7, impart movement thereto. At the under surface of the slide a pin 15 is fixed to which is hinged the one end of the connecting rod 16 the other end of which engages a crank pin 17 fixed to the gear wheel 18. Gear wheel 18 is mounted to rotate on a stationary pin 19 within the head A. This wheel meshes with the pinion 21 fixed to the motor shaft 20. Motor shaft 20 is supported in the lower end of the stator and in the bearing 22.

In a modified form (see Fig. 2b) the plate 1a is flat on its upper surface and the flexible razor-blade 7a is transversely curved. The blade placed on the plate 1 is bent approximately flat by the pins 28 of the cover 23, when the cover is placed on the head. The cutting edges of the razor-blade may be either straight or toothed.

The shaving blade 7 is protected by the cover 23 which is clamped by means of two clips 25 to two lugs 24 formed on the head A. The cover 23 is provided with two notches 26 receiving the ears 27 extended at both ends from plate 1, so that the cover maintains always the same spacing from blade 7 and plate 1. The pins 28 of the cover are extended between the pins 9, 10 and 11 and bear upon blade 7 to press it against plate 1 bending the blade resiliently downwards so that the cutting edges of the blade are in tight contact with the outer edges of the holes 6 of plate 1. Laterally of the head A an ejector rotatably mounted which is composed of a medial portion 30 pivoted in the head and terminal lever arms 30 and 31. The lever arm 31 lies underneath blade 7 so that after the removal of cover 23 and the swinging of lever 29, the blade 7 will be lifted off to be changed if need be. When the motor is started the device is held with the cover in tight contact over the skin to be shaved and the hairs will project into the holes 6 and will be shaved off by the cutting edge of the blade while the respective portion of the skin is held fast.

The rows of holes 6 are disposed on both sides of head A and beyond the exterior surface of the latter so that the hairs cut-off are discharged from the holes without obstructing the same. This arrangement permits the using of the tool not only for dry shaving but also in connection with soap or cream. In the latter case the straight protecting edges of the plate 1 strip off the soap lather from the edge of the blade and only very little can penetrate into the inside of the tool.

Instead of a slide as shown in Figs. 1 to 3, a second form of slidable motor driven plate 32 might be provided underneath the stationary plate 1 as shown in Figs. 4 to 6, the slidable plate being guided in slots 33 disposed at an acute angle with respect to the middle line of the head A by means of the bolts 2 used for fastening plate 1. To the upper surface of plate 32 pins 9b, 10b, 11b are fixed, which serve for transmitting the movement to the shaving blade 7. On the under side of plate 32 a screw 15 connects one end of the connecting-rod 16 with the slidable plate 32. The other end of the connecting-rod is attached to the pin 17 which imparts a reciprocating movement to plate 32 when the motor is

started. The edges 32a of plate 32 are chamfered on the upper side to deflect the cut hair discharged from the holes 6. Rollers 34 provided underneath plate 32 are pressed upwards by the helical springs 36 and sleeves 35 engaging the upper ends of the springs. The lower ends of the springs are engaged by pins 37 which bear against the cams 38 of the regulating ring 39 provided with two diametrically opposed handles 40 projecting through slots G by which said ring may be adjusted for regulating the tension of the springs 36. Thereby the pressure upon the rollers 34 may be increased or lessened and the slidable plate 32 may be pressed more or less, against plate 1. If the pressure is increased the frictional contact between the plates 1 and 32 is increased and the speed of the tool is lessened, whilst the speed will be increased if the pressure is lessened. Thus the speed of the tool may be regulated by operating the regulating ring 39.

The slidable plate 32 carries also a down-turned part with a threaded hole 41 into which may be screwed a massage member or other like member so that the tool may also be used for slight massaging. A fan 42 fixed to the motor shaft 20 is intended for circulating air and cooling the motor. Plate 1 (see Fig. 5a) as in the first embodiment is hollowed at its center portion so as to effect the contact of the shaving blade only between its cutting edge and the plate edges. In a modified form (see Fig. 5b) the plate 1 is plane and the blade 7 curved. The blade is bent flat when the cover is placed in position. The cover 23 protecting the blade presses the blade by means of the pin 28 resiliently downwards and effects the good contact between cutting edges and plate 1. After the removal of cover 23 the shaving blade may be ejected by swinging lever 29 as in the form of invention illustrated in Figs. 1 to 3.

Figures 8 to 11 show another embodiment consisting of a combination of the shaving tool with a hair cutting device. To this end one side of plate 1 is provided with cutting teeth 43 and the corresponding side of the slidable motor driven plate underneath said stationary plate 1 is provided with teeth 44. Both rows of teeth cooperate during hair cutting. The other side of the stationary plate is provided with holes 6 as above described. The plate 1 is hollowed (see Fig. 9a) for a flat blade or flat (see Fig. 9b) for a curved blade.

The slidable motor driven plate may, according to Fig. 10, be made in two parts 45 and 51. The part 45 serving as shearing plate is provided with two slots 46 parallel to the row of teeth, plate 45 being guided on bolts 2 in a direction parallel to said slots. A screw 47 with a resilient disk screwed to plate 1 serves for pressing plate 45 against teeth 43 of the stationary plate. On the side opposite the shearing teeth 44 two noses 48, 49 are formed. The nose 49 is connected with the connecting rod 16 transmitting the movement of crank pin 17 to the slidable plate 45, the rod 16 being located below the part 45. The nose 48 is connected with the member 51 by a connecting link 50 and transmits the to and fro movement to this member, the link 50 being located above the member 45. The other part 51 of the motor driven plate is guided on pins 2 by the slots 52 disposed at an acute angle with respect to the axis of the plate part. These slots effect the displacement of the shaving blade obliquely and lengthwise during the reciprocating movement of the part 51. The three pins 9, 10 and 11 serve for

transmitting the movement of the part 51 to the shaving blade 7, said pins projecting upwardly through the longitudinal opening 8 in the stationary plate and are engaged in the holes of the shaving blade 7 from underneath. The outer edge 32a of the guide member 51 is chamfered on the upper side downwards. An extension with a threaded hole 41 permits the attachment of a massage member or the like to the part 51.

The motor driven plate may also comprise one single piece as indicated at 32c in Figs. 8 and 11. Here the plate is provided on one side with teeth 44 cooperating with the teeth 43 of the stationary plate 1 for hair cutting. Slots 52 serve as guides and engage the bolts 2 of the stationary plate 1, said slots being arranged at an acute angle with respect to the middle line of head A whereby during the reciprocating movement of the part 32c, it together with the blade 7 will be displaced on the stationary plate 1 and the row of holes 6 in an oblique direction. By turning the regulating ring 39 and cams 38 by means of handles 40 the rollers 34 may be pressed more or less against the stationary plate and thereby the speed of the tool may be regulated. The cover 23 protects the blade 7 and bends this blade by means of the pins 28 towards plate 1 to bring the cutting edges of the blade into close contact with the edges of holes 6.

In the various embodiments described gears 18 and 21 have been provided between motor shaft 20 and the connecting rod 16 of the tool so that the speed of the tool may be changed by varying the gear ratio, but it will be understood that the crank pin operating the connecting rod may be attached directly to the motor shaft.

The usual rectangular shaving blade now in extensive use may be used in the improved razor as well as blades provided with small teeth.

Since the constructive part of the tool such as shown may be changed so long as this is done without departing from the scope of the invention claimed it is understood that the embodiments represented in the annexed drawings are to be considered only as examples.

What I claim is:

1. In a shaving device, a stationary plate having a skin contacting surface and cavities presenting cutting edges at said surface of the plate, a reciprocating razor blade overlying said surface of the stationary plate, means for reciprocating the razor blade, and means for maintaining the razor blade in close contact with said surface of the stationary plate.

2. In a shaving device, a stationary head having a skin contacting surface and a handle secured thereto, a stationary plate having a skin engaging edge and cavities lying inside said edge presenting cutting edges at said surface of the plate, said plate being mounted on said head, a reciprocating razor blade overlying said surface, and means for maintaining said razor blade in close contact with said surface.

3. In a shaving device, a stationary blade having a skin contacting surface and a skin engaging edge and cavities lying inside said edge presenting cutting edges at said surface of the blade, a reciprocating rectangular razor blade overlying said plate and movable across said surface and said cutting edges, means for reciprocating the razor blade, a cover arranged over said razor blade and stationary plate, members carried by said cover for maintaining the edges of the razor blade in close contact with the surface of the stationary plate.

4. In a shaving device, a stationary plate having a skin engaging edge and cavities lying inside said edge presenting cutting edges at one surface of the plate, a perforated reciprocating plane razor blade overlying said surface, a slide with guides inclined to the edge of said blade, vertical pins on said slide operably engaging the perforations in the razor blade, a motor driven crank for reciprocating the slide and the razor blade, a cover clamped resiliently over said blade, and means for maintaining the edges of the razor blade in close contact with said surface of the stationary plate.

5. In a shaving device, a stationary plate having a skin engaging edge and cavities lying inside said edge presenting cutting edges at one surface of the plate, a perforated reciprocating transversely curved razor blade overlying said surface, a slide with guides inclined to the edge of said blade, vertical pins on said slide operably engaging the perforations in the razor blade, a motor driven crank for reciprocating the slide and the razor blade, a cover clamped resiliently over said blade, pins fast on said cover for maintaining the edges of the razor blade in close contact with said surface.

6. In a shaving device, a stationary plate having a skin engaging edge and cavities lying inside said edge presenting cutting edges at one surface of said plate, a perforated reciprocating razor blade overlying said surface, a slide with guides inclined to the edge of said blade, vertical pins on said slide operably engaging the perforations in the razor blade, a motor shaft, a crank and connecting rod between the shaft and slide for reciprocating the razor blade, a cover clamped resiliently on said plate, a disc on said shaft, a flat spring frictionally engaging said disc, a manually rotatable ring, downwardly directed cams on said ring cooperating with said flat spring to vary frictional contact with said disc, the spring being adapted to be bent by said cams.

7. In a shaving device, a stationary plate having a skin engaging edge and cavities lying inside said edge presenting cutting edges at one surface of said plate, a perforated reciprocating razor blade overlying said surface, a movable plate with slots inclined with respect to the edge of said blade, guide bolts on said stationary plate engaging said slots, vertical pins on said movable plate operably engaging the perforations in the razor blade, a motor shaft, a crank and connecting rod between said shaft and said slide for reciprocating the razor blade, a manually rotatable ring, a disc on said shaft, a flat spring frictionally engaging said disc, cams on said ring cooperating with said spring to vary frictional contact with said disc, the spring being adapted to be bent by said cams.

8. A shaving device according to claim 7, wherein the plate is concave and the reciprocating razor blade is provided with toothed edges overlying said surface of the stationary plate.

9. A shaving device according to claim 7, wherein the plate is flat and said blade is curved.

10. In a shaving and hair cutting device, a stationary plate having a skin engaging edge and cavities lying inside said edge presenting cutting edges at one surface of the plate and teeth on another edge of said plate, a reciprocating razor blade overlying said surface, a reciprocating toothed plate carrying said razor blade and underlying said stationary plate, means for reciprocating the movable plate and the razor blade, and

means for maintaining the razor blade in close contact with said surface and the teeth of the movable plate in close contact with the teeth of the stationary plate.

11. In a shaving and hair cutting device, a stationary plate having a skin engaging edge and cavities lying inside said edge presenting cutting edges at one surface of the plate and teeth on another edge of said plate, a reciprocating razor blade overlying said surface, a reciprocating toothed movable plate with inclined guide slots arranged on the underside of the stationary plate, vertical pins on said movable plate for carrying the razor blade, a crank and connecting rod and a motor for reciprocating the movable plate and the razor blade, a cover arranged over said stationary plate, pins on said cover for maintaining the edges of the razor blade in close contact with said surface, a rotary manually operated ring, upwardly directed cams on said ring, spring pressed rollers for adjustably pressing the movable plate against the stationary plate, and means coacting with said cams for varying the spring pressure exerted on said rollers.

12. A shaving and hair cutting device according to claim 10, wherein the stationary plate is concave and said blade is flat.

13. A shaving and hair cutting device according to claim 11, wherein said stationary plate is flat and said blade is curved.

14. In a shaving and hair cutting device, a stationary plate having a skin engaging edge and cavities lying inside said edge presenting cutting edges at one surface of said plate and teeth on another edge of said plate, a reciprocating blade overlying said surface, two plates slidably arranged on the underside of the stationary plate, teeth on one of the slidable plates in close contact with the teeth of the stationary plate, carrying pins on the other slidable plate engaging the razor blade, guides on the stationary plate for the two slidable plates, a link connecting the two slid-
able plates, a motor driven crank for reciprocating the two slidable plates and the razor blade, a cover arranged over said stationary plate, means for maintaining the edges of the razor blade in close contact with said surface of the stationary plate, a manually operable ring, cams on said ring, rollers for adjustably pressing the two slid-
able plates against the stationary plate, and pres-
sure applying means for said rollers controlled by
25 said cams.

RUDOLF NAEGELI.
